FIRE DETECTING APPARATUS

Serge N. Koulichkov, New York, N. Y., assignor of
thirty per cent to Elmon C. Gillette, New York,
N. Y.

Application May 28, 1936, Serial No. 82,310

6 Claims. (Cl. 177—355)

My invention relates to fire detecting apparatus and has particular reference to apparatus employing photocells and thermoelements.

The object of my invention is to provide an apparatus which will have a photocell with a circuit and relay for sending signals, so arranged that the relay will be energized by a moving light only. Such an arrangement is necessary in order to prevent receiving signals when the photocell is subjected to ordinary changes in illumination, bright sun, etc. The fire of any origin, as a rule, rises more or less rapidly in the form of sheets of flame or sparks. At the day time the fire may be preceded or accompanied by clouds of smoke, also more or less rapidly rising, thereby having the same effect on the photocell.

An ordinary photocell generates a direct current when illuminated by a stationary or moving source of light. I construct my photocell in such manner, however, that it will produce alternating current when illuminated by a light moving in a certain direction. For this purpose I provide my photocell with photosensitive grids at a distance apart and in the path of light rays, the grids being formed of parallel bars with slots between them. The result of such an arrangement is that a light, or an image, moving across the grids, produces a flickering effect, being broken up by the grids, which will therefore generate an intermittent or pulsating current. I direct this current into the primary winding of a transformer, which converts it into an alternating current. It is evident that no current will be induced in the secondary of the transformer if the primary receives a steady direct current, such as may be generated by the illumination from the sun, moon, etc.

The frequency of pulsations may be increased by the introduction of condensers in the primary circuit.

I prefer to arrange the grids in a horizontal direction as the fire and smoke rise more or less vertically thereby producing the greatest effect on the horizontal grids.

Another object of my invention is to provide a photocell whose contacts are connected in series with a thermocouple, both the photocell and the thermocouple having their contacts connected with corresponding relays. These relay contacts are connected in series with a signal sending apparatus so that the latter becomes operative when both, the photocell and the thermocouple, are energized. With this arrangement signals are transmitted only in case a light is accompanied

by a rise in temperature, and the apparatus will not be operative if it receives light from such objects as automobile headlights, even if they are moving, rising clouds of fog, etc.

Another object of my invention is to provide a housing for the photocell and thermocouple rotatively mounted and connected with a mechanism for rotating the housing at a steady rate for scanning the horizon for fires. For this purpose I provide a gearing and a motor, either electric or spring operated, and also provide a wind motor for charging the battery, supplying current to the motor, or for winding the spring if a clock mechanism is used. In order to render the action of my photocell more effective, I provide the gearing of an intermittent type, so as to cause the housing to stop for short periods every few degrees of its rotation.

Another object of my invention is to provide a mechanism for stopping the rotation of the housing for a certain length of time when the photocell is energized in order to have sufficient time for sending signals to a central station.

Another object of my invention is to provide means to transmit signals by radio to a central control station when a fire has been detected, indicating also the direction or azimuth of the fire. For this purpose I provide a recording mechanism at the central station, indicating on a moving sheet of paper the signals as they are received from each detecting apparatus. I also provide means for sending separate signals when the housing with the photocell passes in its rotation through a definite point, preferably north. By measuring the distance on the paper between the fire signal and the north signal it is possible to establish the azimuth of the place at which the fire originated.

As a modification, I also provide means for sending different signals for each position of the housing in its rotation, thereby directly indicating the azimuth of the fire.

Another object of my invention is to provide means to operate the radio transmitter and to use the electric current when there is a fire only, and to render the north indicating signals operative when the fire signals are being transmitted only.

Another object of my invention is to provide means to send control signals at certain intervals of time as an indication that the apparatus is properly functioning.

Another object of my invention is to provide an arrangement with my photocell and thermocouple for sending fire alarms in buildings. For

this purpose I employ a stationary housing with my fire detecting elements and I also employ mirrors in order to enlarge the area served by the detecting apparatus.

5 Another object of my invention is to provide means controlled by my fire detecting element for operating an ordinary telephone apparatus so as to send an alarm to a telephone exchange, this means being applicable to any type of telephone apparatus.

As is well known, forest fires cause a great damage, destroying valuable timber, endangering lives and property in villages and cities situated in wooded areas, also ruining the land for re-15 forestation and cultivation.

According to statistical data for the United States, in 1926-1930 there were on the average 156,183 forest fires every year, destroying annually 41,538,876 acres of forests and causing an 20 annual damage of \$62,831,423. There was little change in the subsequent years, and in 1934, for instance, there were about 42,200,000 acres destroyed.

The damage would have been much greater if 25 there were no steps taken to prevent the forest fires. Every year a larger area of forest lands becomes protected by lookout stations employing watchmen, constantly scanning their assigned areas for fires. Thus, for the period from 30 1926 to 1930 there were 63.9% of protected forest lands, yet the damage to the unprotected areas greatly exceeded the damage to the protected forests: while the first was on the average \$51,525,160 per annum, the second was only \$11,306,-35 263.

The present method of fire protection is not very effective, too much dependence being necessarily placed on the watchfulness of the men on the lookout stations; and, besides the cost of 40 maintaining such lookout stations with wages to the men for day and night shifts, with relief men also on the payroll, is very high.

With my invention it is possible to render the 45 fire detection entirely automatic, with more thorough scanning of the respective areas regardless of the profile of the country, operating continuously day and night and for a relatively longer period every year, in any kind of weather.

My system employs radio apparatus so that it 50 does not depend on the availability of telephone service for the detection of forest fires and does not require construction of special transmission lines. It is self contained and has its own means for recharging storage batteries used with the 55 radio apparatus.

My system in a modified form is also applicable to the detection of fires in buildings and houses, being much more sensitive than ordinary fire alarms, as it gives warning signals immediately 60 after the flames and smoke first appear, so that they can be easily extinguished by watchmen or other attendants. My system can be used to send signals directly to fire stations by special wires, radio or telephones. In the latter case my 65 fire detecting apparatus is connected with relays and magnets operating special attachments to a telephone apparatus for lifting the receiver off its hook and performing other necessary operations to warn the telephone exchange operator, including dialing an automatic call apparatus or inserting a coin if a pay station is available.

The installation of my fire detecting apparatus, being simple and inexpensive, may go far toward 70 considerable reduction if not elimination of the danger of fires in houses, especially in such build-

ings which are used only part of the time, including factories, warehouses, office buildings, churches, etc.

The detecting apparatus can simultaneously ring the bell to a watchman and send special signals by a telephone to the exchange or other office, from which immediate help can be sent or ordered. Any type of telephones can be used, as well as a radio transmitter, sending signals on a special wave, there being a separate transmitter for each building, or one transmitter for a group of buildings.

5 My photocell can be used for detecting any moving objects. It can be used, for instance, for sending signals when a train passes a certain point, for recording passing vehicles, airplanes, boats, etc.; also for operating traffic lights when an automobile approaches a crossing in places where traffic is light. It may be used as a burglar alarm, for detecting the presence of a moving 10 warm object in the dark.

15 My invention is more fully described in the accompanying specification and drawings in which—

20 Fig. 1 is a diagrammatic view of my fire detecting apparatus in connection with a rotating housing and a wind motor-generator, Fig. 2 is a detail view of my photocell, Fig. 3 is a sectional elevation of an apparatus for detecting forest fires corresponding to Fig. 1, Fig. 4 is a detail view of a central fire recording apparatus, Fig. 5 is another view of the same, Fig. 6 is a diagrammatic view of a modified device, Fig. 7 is a view of another modification, Fig. 8 is a diagrammatic view of a device for sending special signals for 25 each position of the rotating apparatus, Fig. 9 is another view of the same, Fig. 10 is a diagrammatic view of a relay, Fig. 11 is a diagrammatic view of an arrangement for detecting fires in buildings, Fig. 12 is a diagrammatic plan view 30 of the same, Fig. 13 is an elevation of a mechanism for signaling through a portable telephone, Fig. 14 is a top plan view of the same, Fig. 15 is a detail view of the same, Fig. 16 is a front view partly in section of a mechanism for signaling 35 through a wall type telephone apparatus, Fig. 17 is a side view of the same partly in section, Fig. 18 is a detail view of a coin depositing device, Fig. 19 is a diagrammatic view of a fire detecting apparatus for houses with a radio transmitter, Fig. 20 is a detail view of a photosensitive grid, 40 and Fig. 21 is a detail view of a recording apparatus employing tuning forks.

45 My fire detecting apparatus consists of a photocell 1 having an anode 2 and a cathode 3 with 50 leads 4 and 5 extending outside through bushings 6. The anode and cathode are made in the form of grids as shown in detail in Fig. 20, the bars of the grids being in parallel alignment. The 55 cathode may be made of any suitable photosensitive material, such as caesium on a silver oxide basis, and the cell may be filled with a suitable gas, such as argon. Any other type of photocell 60 may be also used, employing, for instance, copper with cuprous oxide for the grid 3, the grid 2 65 not being connected to the circuit and serving only to break up the light in such a case. The grid 3 or both, 2 and 3, may be made of selenium and connected in series across a battery. The 70 photocell is supported in a housing 7 having a narrow vertical slot 8 in one wall. A condenser lens 9 gathers rays 10 from the slot 8 and directs them into a window 11 in the cell 1, a concave lens 12 being placed in the window for straightening the rays into a parallel-sided beam. The 75

leads 4 and 5 are connected to the primary 13 of a transformer 14, the secondary 15 being connected through condensers 16 with a relay 17 in the circuit of leads 18 and 19.

5 A thermo-sensitive element or thermocouple 20 is also placed in the path of rays from the window or slot 8 and is connected by leads 21 and 22 with a relay 23 in the circuit of leads 18 and 24.

10 The photocell and the thermocouple may be placed side by side as shown in Fig. 1 in which case part of the light from the window 8 may be deflected by a prism 25 which may be also condensing or convex. The slot 8 is protected by an extension 26 on the wall of the housing with a slot 27 in line with the slot 8, the sides of the slots forming an angle α of a few degrees. A mica window 31' is placed over the slot.

The housing 1 is connected by a universal joint 28 with a vertical shaft 29 journaled in a bearing plate 30 supported in the upper portion of a stationary housing 31. The shaft 29 has a gear 32 in mesh with a pinion 33 connected by a gear 34 with a pinion 35 on the end of a shaft 36 of an electric motor 33 connected by leads 37 and 38 with a storage battery 39. A generator 40 is mounted on a vertical shaft 41 supported in a bearing 42 and is provided with a rudder 43 for directing it with the wind so that propeller blades 30 of a wind motor 44, mounted on the end of the generator shaft, will always face the wind. An automatic charge regulator 45 is placed in the charging circuit of leads 46 and 47 extending from brushes 48 in contact with collector rings 49 on the end of the shaft 41.

35 The gear 34 and pinion 35 are of a form adapted for intermittent rotation as shown in Fig. 1. With this arrangement the housing 1 stops at short intervals, usually a few degrees, for a few seconds in order to enable a light from a fire to produce its effect on the photoelectric cell and thermoelement.

The leads 19 and 24 are connected to brushes 42 supported on a flange 43' on the shaft 29. 45 The brushes are in contact with collector rings 44 and 45 mounted on an insulation plate 46 supported on the plate 30 in the upper portion of the stationary housing 31. A radio transmitter 47' with one or more radio tubes 48' is mounted on a floor plate 49' of the housing 31. The plate 49' is supported on top of a tower made of beams 50 situated so that the housing 1 in its rotation can scan a large area of forest land. In order to follow the curvature of land in a hilly country, the housing 1 is provided with rollers 51 following a circular or ring-shaped cam 52, formed in accordance with the contour of the land.

50 A flexible apron 54, preferably made of a waterproof material, such as rubber, is attached to the lower edge of the rotary housing 1 and fits over the conical upper portion of the stationary housing 31 in order to protect the inner mechanism from rain, dust or snow.

55 The heated filament of the tube 48' is connected with the battery 39 through a relay switch 55. The latter is connected with a rod 56 moving with slight friction inside of magnet coils 57 and 58. An armature 59 on the rod may be attracted by either magnet. The coil 57 is connected with the battery through a switch 60 which is normally open under action of a compression spring 61. The other coil 58 is connected in series with the transmitter 47'. The other end of the rod 56 is pivotally connected with an arm 62 rotatively supported by one end on a pivot 63 and having on

the other end a star wheel 64 which can turn in the forked end of the arm 62. A lug 65 on the wheel engages the switch 60, closing it once during each revolution of the wheel, when turned in the direction of an arrow 66. The wheel, when moved outward on its pivot by the rod 56, is engaged by a finger 67 the latter being shown diagrammatically in Figure 1 extending from the housing 1 or from any suitable rotative part connected with the housing, so that the wheel 64 is turned through an angle between its two teeth with each revolution of the housing 1.

10 The collector rings 44 and 45 can be short circuited by a relay switch 68 having a rod 74 sliding with a friction in magnet coils 69 and 70 and having an armature 71 which can be attracted by either coil. The coil 69 is connected in series with the radio transmitter 47, and the coil 70 is connected with the battery 39 through a switch 72. The arm 73 of the switch is moved 20 by the finger 67 once during each revolution of the housing 1, closing the switch 72.

15 A star wheel 75 is rotatively supported on a shaft 76 and is engaged by the finger 67 once during each revolution of the housing 1. A pinion 77 on the shaft 76 is in mesh with a gear 78 having a finger 79 adapted to close a switch 80 for short circuiting the rings 44 and 45. The gears between the wheel 75 and the finger 79 are so arranged that the switch 80 is closed once in a 30 few hours; for instance, once in six hours. The switch 80 is normally open under action of a spring 81, while the switch arm 73 is open under action of a spring 82 (81 and 82 being compression springs).

25 Radio signals are transmitted by an antenna 83 to a central control station where there are separate relays for each station with a detecting apparatus, different transmitters being tuned to send different wave lengths so that each receiving relay responds to one particular sending station only. The relays (not shown) operate magnets 84 pressing arms 85 with pencils or pens 86 against a sheet of paper 87 continuously moving between cylinders 88.

30 The operation of my apparatus is as follows.

The housing 1 continuously rotates, scanning the horizon with its slot 27. The driving mechanism is so arranged that it takes a few minutes for one complete revolution, with 50 or 60 stops, so as to make steps of about 6 or 7 degrees between the stops. The radio transmitter is not operating during the rotation of the housing, except that once in 6 hours (or after other suitable intervals) the arm 79 closes the switch 80 35 for a short time, thereby short circuiting the rings 44 and 45 and connecting the cathode circuit of the tube 48' in the transmitter 47' with the battery. The transmitter may be of any construction and its circuits are not shown, it 40 may have a by-pass resistor for the current to flow into relay coils 69 and 58. Its tube 48' may represent an oscillator for sending radio waves through a tuned circuit of an ordinary type connected with the antenna 83, the waves being 45 generated when circuit is closed for the cathode of the tube by the relays 17 and 23 or by the switch 68 or 81, while the filament is heated by the battery through an independent circuit including the coil 58.

50 Current then passes through the coil 69 which attracts the armature 71 thereby closing the switch 68 so as to continue the operation of the transmitter independently of the relays 17 and 23. The coil 58 is now energized and attracts 55

the armature 59, closing the switch 55 and energizing the filament of the radio tube. The relative positions of the finger 67 and lug 79 are so arranged that the finger 67 closes the switch 72 when the slot 27 passes through the north or zero degrees, and the lug 79 closes the switch 68 a short time before the switch 72 is closed, so that the filament of the tube is already heated for sending a short signal to the corresponding relay and magnet 84. As a result, a short line will be drawn by the corresponding pencil 86, indicating that the particular detecting apparatus is properly functioning. The signal will last only until the switch 72 is closed, by the lug 67 when the coil 70 is energized, attracting the armature 71 and disconnecting the switch 68. The filament will remain hot for a somewhat longer time, until the wheel 64 is turned so that its lug 65 closes the switch 60, energizing the coil 57 and disconnecting the switch 55.

In view of the fact that the thermocouple relay contacts are connected in series with the contacts of photocell relay, it follows that no signals will be sent if there is a rise in temperature unaccompanied by a corresponding lighting effect and vice versa. A steady illumination, however, even if accompanied by heat (for instance, direct or reflected sunrays) will not produce any signals, as a direct current, generated by the photocell, will not pass through the transformer 14. The relay 17 will be energized only in case a beam of light rays moves across the grids 2 and 3 as shown in dotted lines in Fig. 2, the effect being that the grid 3 will be alternately light and dark, thereby generating an intermittent or pulsating current. The latter will produce alternating current in the secondary of the transformer 14.

It is evident that with horizontally arranged grids 2 and 3, a pulsating current will be generated by an image of an object moving in a vertical direction, or at an angle to the horizon. Any light moving horizontally, such as headlights of an automobile, will not produce a pulsating current. The current will be generated not necessarily by a bright moving light, but also by the image of an object darker than its surroundings, causing a flickering change in the illumination of the cathode in the photocell. Clouds of smoke, therefore, will cause current to be generated, regardless of whether they are white or black there being several alternations during the time when the radiant energy from the fire passes through the window 27.

Closing of the relays 17 and 23 will short circuit the rings 44 and 45 with a result that current will flow into the transmitter 47 and coils 58 and 69, closing the switches 55 and 68. The switch 68 will be disconnected as soon as the housing 7 turns with its slot 27 directly to north as it was explained above. The switch 55, however, will remain closed during several revolutions of the housing 7, maintaining the filament of the tube heated until the lug 65 of the wheel 64 opens the switch 60.

Because of a certain length of time required for the filament to become properly heated (not less than 30 seconds), the first signal received at the central station cannot be used for the determination of the azimuth of the place where there is a fire. During the next revolution, however, when the filament is already functioning, a signal will be sent immediately as the housing turns with the slot 27 in the direction of the fire. The corresponding pencil 86 will then

begin to draw a line on the moving strip of paper 81. The switch 68 will remain in a closed position even after the housing turns away from the fire, and the pencil will continue to draw the line until the housing reaches north position with the slot 27, when the finger 67 will close the switch 72, disconnecting the switch 68 and stopping the signal.

The signals will be repeated with every revolution of the housing 7, and the corresponding pencil 86 will every time draw a new line. This line, when measured on a corresponding scale, will give the exact azimuth of the place where the fire was observed. The direction in which the fire was observed by the apparatus can then be plotted on a map on which different apparatus are indicated. If the signals are received from two or three apparatus, then the intersection of the corresponding directions on the map will give the exact location of the fire.

A modified arrangement for recording signals is shown in Fig. 21. Here a row of tuning forks 89 are supported so that their ends with pencils 90 are placed above the paper 81. The tips of the pencils are located at a very small distance 23 from the paper so that they do not leave any marks if the tuning fork remains still. The pencils begin to touch the paper, however, when the forks vibrate. They are made for different tunes, and the receiving apparatus is arranged to reproduce audio frequencies transmitted by various stations. Therefore when a transmitting station sends its own audio frequency, converted into a radio frequency, the common signal received reproduces a tune, which causes a corresponding fork to vibrate by resonance, drawing a line on the paper. With this arrangement it is possible to use one common wave length for all apparatus. The tuning forks may be also placed sidewise in relation to the paper, having their pencil touching the paper all the time and drawing straight lines, turned into zig-zag when a fork is vibrating.

A modified arrangement of the apparatus is shown in Fig. 6 in which the housing 7 is not shown. A switch 91 is provided for the motor 53 and is opened by a collar 92 on a rod 93 which slides in magnet coils 94 and 95. A brake drum 96 is mounted on the shaft 36 of the motor and is engaged by an arm 97 on the end of the rod 93. An armature 98 on the rod is attracted by the coils.

A jaw clutch 99 is fitted on the lower end of the rod 93 engaging a toothed wheel 100 rotated by a clock mechanism 101. A finger 102 on the wheel 100 closes a switch 103. An extension 104 on the rod 93 opens the switch 103 in its downward movement and opens a switch 105 when moved upward. The coils in this modification are shown connected in parallel with the radio transmitter.

The operation of this arrangement is as follows.

As soon as the fire detecting relays are closed, the magnet coils 69 and 94 will be energized. The switch 68 will be closed and the switch 91 opened, disconnecting the motor 53, which will also be stopped by the application of the braking arm 97 against the drum 96. Upon completion of these operations the coil 94 will be disconnected by the switch 105 opened by the extension 104. The housing 7 will be standing still in the position in which the fire was detected. The jaw clutch 99 will release the clock mechanism 101, and the wheel 100 will start turning. Upon completion of one revolution, the finger 102 will close

the switch 103, energizing the coil 85. The rod 93 will accordingly move downward, releasing the brake and closing the motor switch 91, stopping also the rotation of the wheel 100. The time 5 of one revolution of the wheel 100 is arranged so that the housing 1 will remain stationary for a few minutes in order to send radio signals and to bring the pencil 86 against the paper 87 in the recording apparatus. The pencil will continue 10 drawing the line until the switch 12 is closed at the north position of the housing. With this arrangement the record will be made the first time when the image of a fire falls on the detecting elements in the housing, and the recording line will 15 be drawn with every revolution of the housing as long as the fire lasts.

Another modification is shown in Fig. 7. The housing 1 (not shown) is operated by a shaft 106 extending from a clock mechanism 107 operated 20 by a spring 108. The latter is connected by an ordinary winding ratchet wheel (not shown) with a shaft 109 having a bevel gear 110 on the other end in mesh with a gear 111. The latter is mounted on the end of a vertical shaft 112 extending from a bearing bracket 113 under the plate 49' and having a bevel gear 114 on the end in mesh with a gear 115 on a shaft 116. The latter is journaled in bearings 117 and has a rudder 43 on one end and a wind-motor 44' on 25 the other. The wind motor keeps the spring 108 wound at all times and thereby maintains constant rotation of the housing 1. An auxiliary electric motor 118 is provided connected by gears 119 and 120 with the shaft 109. A switch 121 connecting the motor with the battery 39 is normally open but may be closed by a plunger 122 pushed outward by the spring 108 when the latter is completely unwound. This may happen if 30 there is no wind for several days, in which case the motor rewinds the spring. The motor stops again as soon as the spring is wound enough to recede from the plunger 122.

The filament of a tube 48' is energized when a switch 55 is closed by a rod 123 under action of 45 a magnet coil 124. The rod 123 at the same time turns a lever 125 on its pivot 126 bringing a gear 127 in mesh with a pinion 128 which is rotated by the clock mechanism. The gear 127 makes one revolution in several minutes or during several 50 revolutions of the housing 1, and during that time the tube remains energized, until a finger 129 closes a switch 130, energizing a coil 131 which moves the rod upward, disconnecting the switch 55 and disengaging the gears 127 and 128. The 55 rod 123 remains by friction in either of its positions.

A switch 13 closes the circuit through the transmitter 47 being pressed by the finger 67 against a contact point 132 once during each 60 revolution of the housing 1 and in the north position of the slot 27 (Fig. 1). With this arrangement, therefore, the fire indicating signal is sent only while the housing is directed toward the fire by its slot 27, and a second signal is sent 65 when the housing passes the north position. Two points or short dashes are recorded on the paper 87 on the receiving apparatus, and the distance between these two points determines the azimuth 70 of the fire. No signals are transmitted unless there is a fire, except that once in 6 hours (or once in 12 or 24 hours, depending on the gearing arrangement) a finger 134, rotated by the clock mechanism, closes a switch 133 for sending a control signal. The switch 133 is closed for a suffi-

ciently long time for the tube to become operative.

Figs. 8 and 9 illustrate an arrangement for sending individual signals for each position of the housing in which the latter stops for a short time because of the arrangement of the intermittent gears 34 and 35. For this purpose a lead 135 from the transmitter 47 is connected with a brush 136 touching a commutator 137 turning at the same rate as the housing 1 and having 10 the same number of segments as the number of stops of the housing during one revolution. The segments are insulated from each other and are in contact with brushes 138 connected by wires 139 with brushes 140 in contact with insulated contact rings 141. The number of wires 139 and rings 141 corresponds to the number of the segments on the commutator 137. The rings 141 are mounted on a drum 142 connected by gears 143 with the commutator so that the drum 20 makes several complete revolutions while the commutator turns through an angle corresponding to one segment.

The rings 141 have slots 144 filled with insulation and spaced so as to produce short and long 25 interruptions in the current through the transmitter thereby sending signals in the form of dots and dashes in the Morse or other system. The signals are different for each position of the housing so that the azimuth of a fire is indicated directly.

My detecting elements can be also used for detecting fires in houses. The cell 1 (Fig. 11) is mounted by a swivel 145 on a bracket 146 supported on a wall 147 of a building. The cell is 35 inclined so as to be directed into a corner where a fire may originate or so as to control the largest area from which rays may be collected by a condenser lens 148. A relay 17 closes the circuit from a battery 39 or other source of 40 electric current, on an electric bell 149. Leads 150 may be also extended to other signaling devices. Mirrors 151 may be employed for reaching 45 corners, corridors or other rooms with the same fire detecting cell.

The leads 150 may be connected to a magnet 152 for operating a signaling mechanism in connection with an ordinary desk telephone 153, as shown in Figs. 13, 14 and 15. The telephone is placed on a raised platform 154 on a base 155. The receiver 156 is placed over a hook 157 on the end of a lever 158 rotatively mounted on a shaft 159 between standards 160. A spring 161 tends to turn the lever 158 and to raise the receiver off the hook 157, but the lever is prevented from turning by a post 163 fitted under the extension of the lever. The post is pivoted at 164 and has an armature 165 for the magnet 152. When attracted by the magnet, the post takes position indicated with dotted lines, releasing the lever, which comes to rest against a lug 166 with the receiver in the raised position. Ordinarily the post 163 is held in the position shown in Fig. 13.

The post 163 is connected by a rod 167 with another post 168 pivoted at 169 and supporting the end of an arm 170 rotatively mounted on a shaft 171 between standards 172. A spiral spring 173 tends to turn the arm 170 into a position shown with dotted lines. The other 70 end of the arm 170 has a mechanism for turning a dial 174 of the telephone. This mechanism consists of a disc 175 on a shaft 176 journaled in the end portion of the arm 170 and connected with a spiral spring 177 which tends to turn 75

the disc in clockwise direction when placed over the dial. The disc has a slot 178 engaged by a lug 179 on a plunger 180 which thereby keeps the disc from turning. A spring 181 retains the plunger 180 in its locking position being held at the other end by a head 182. The plunger has an extension 183 adapted to rest against the telephone base 153 when the arm 170 is turned, the plunger in this position releasing the disc 175. The disc has a pin 184 adapted to enter the hole in the dial marked "0" which serves for calling an operator at the telephone exchange. A tapering cam 185 on the disc is adapted to engage the raised hook 186 on the dial.

15 The magnet 152, when energized, attracts the armature 165, pulling the posts 163 and 168 from under the ends of the members 158 and 170. The lever 158 raises the receiver being pulled by the spring 161, and the arm 170 turns over, 20 pressing the disc 175 against the dial 174 with the pin 184 entering the hole "0" in the dial. The plunger 180 is pushed upward, releasing the disc and permitting the latter to rotate under action of the spring 177 until at the end of the 25 rotation the cam 185 meets the hook 186 and, climbing on it, raises the disc and the arm 170 so that the pin 184 leaves the hole "0", permitting the dial to return into its original position, the call to the operator meanwhile having been 30 made.

A rubber bumper 187 is provided for softening the blow of the arm 170 when it comes to rest against the dial. The bumper is supported on posts 188.

35 A similar mechanism is shown in Figs. 16, 17 and 18 for a wall type telephone 189 with a receiver on a hook 190, a dial 174 and coin slots 191, 192 and 193. The hook 190 is engaged by a hook 194 on a sliding rod 195 guided in bearings 196 and 197. A spring 198 tends to raise the rod 195, this spring being stronger than a spring 199 supporting the hook 194 which slides on the rod 195. A latch 200 engages a collar 201 on the rod, keeping the spring 198 compressed 45 and the rod in its downward position. A magnet 202, when energized, pulls the latch, releasing the collar 201 and the rod 195. The latch is pivoted at 203. The other end of the rod is pivotally connected with a link 204 connected 50 at the other end also pivotally with the end of a crank 205 on a shaft 206 journaled in bearings 207. The shaft 206 carries an arm 208 with a dialing mechanism on the end similar to the one shown in Figs. 13, 14 and 15. A shorter arm 55 209 is also mounted on the shaft 206 and has on the end a coin inserting mechanism consisting of a depression 210 for a coin or slug 211 retained by a spring 212 with a tongue 213. The spring is made so that it releases the coin 60 when the tongue 213 strikes the surface of the telephone box 189, releasing the coin, which then is thrown into the slot 193. The spring 199 is provided in order to have a shorter travel for the hook 194 than for the rod 195, the latter 65 being sufficiently long to operate the crank 205.

It is understood, of course, that the arm 208, as well as the arm 170, may be placed at the side of the telephone if it is preferable to render the telephone more accessible.

70 A cover 214 is placed over the shaft and bearings with slots 215 for the arm 208, and a hood 216 over the arm 209 in order to render it difficultly accessible so as to prevent the theft of a coin or slug held by the spring 212.

75 The arm 208 is omitted if the telephone has

no automatic dial; likewise, the arm 209 is omitted if there are no coin slots. In the latter case the mere raising of the receiver with no one to speak serves as a warning to the telephone exchange that there is a fire in the building, especially if the operation takes place at night or at a time when the building is supposed to be unoccupied.

Further modifications of my device may be made without departing from the spirit of my invention, as, for instance, by applying my apparatus for signaling the passage of a train, boat, a person or animal at night, etc.

I claim as my invention:

1. A fire detecting apparatus comprising a 15 housing with a slot in its wall, an element in the housing adapted to generate electric current when subjected to the action of a radiant energy from a fire, means to rotate the housing, an electric circuit including a radio transmitter adapted 20 to send signals, means to close the circuit when the element is energized, means to maintain the circuit closed, and means to open the circuit when the housing reaches in its rotation a predetermined compass position in its rotation, the 25 length of the signal thereby corresponding to the angular distance of the radiation emitting point to said compass position.

2. A fire detecting apparatus comprising a 30 housing with a slot in its wall, an element in the housing adapted to generate electric current when subjected to the action of a radiant energy from a fire, means to rotate the housing, an electric circuit including a radio transmitter adapted 35 to continuously send signals, relays adapted to close the circuit by the current generated by the element, a relay adapted to be closed by the current in the circuit for closing the latter independently of the relays in the element circuit, and means on the housing for opening the circuit 40 when the housing slot is directed against a certain point on the horizon, the length of the continuous signal thereby corresponding to the angular distance between the fire and the fixed point on the horizon.

3. A fire detecting apparatus comprising a 45 housing with a slot in its wall, an element in the housing adapted to generate electric current when subjected to the action of a radiant energy from a fire, means to rotate the housing, an electric circuit including a radio transmitter adapted 50 to continuously send signals, means to close the circuit by the element when it is energized, a wheel rotatively supported at the housing projections on the wheel, means to turn the wheel 55 through a fraction of one revolution with each revolution of the housing, and means to close the circuit for the signals for a short time by the projections of the wheel when the housing completes a predetermined number of revolutions.

4. A fire detecting apparatus comprising a 60 housing with a slot in its wall, an element in the housing adapted to generate electric current when subjected to the action of a radiant energy passing through the slot from a fire, means to rotate 65 the housing, a radio transmitter comprising a radio tube, an electric circuit for energizing the filament in the tube, an electric circuit for generating radio waves by the tube, means to close the two circuits by the element when it is energized, means to maintain the filament circuit closed, and means operated by the housing in its rotation for opening the filament circuit upon completion of several revolutions of the housing.

5. A fire detecting apparatus comprising a 75

housing with a slot in its wall, an element in the housing adapted to generate electric current when subjected to the action of a radiant energy and passing through the slot from a fire, means to 5 rotate the housing, a radio transmitter comprising a radio tube, an electric circuit for energizing the filament in the tube, an electric circuit for generating radio waves by the tube, means to close the two circuits by the element when it 10 is energized, a wheel rotatively supported at the housing and having a plurality of projections, a lug on the housing adapted to engage the projections for turning the wheel a fraction of one revolution for each revolution of the housing, means to maintain the filament circuit closed 15 after it has been closed by the element, and means to open the filament circuit by the wheel upon completion of its revolution.

6. A fire detecting apparatus comprising a 20 housing with a slot in its wall, an element in the

housing, a circuit for the element including a relay, the relay being adapted to be closed when the element is subjected to the action of a radiant energy passing through the slot from a distant fire, a radio transmitter comprising a radio tube, 5 a circuit for energizing the filament of the tube, a circuit for generating radio waves by the transmitter, means to close the filament circuit by the relay, means to close the wave generating circuit by the relay, means to retain the filament closing circuit closed, a toothed wheel, a movable support for the wheel, means to move the wheel outward by the filament circuit closing means, means to rotate the wheel a fraction of one revolution by the housing with each revolution of the 10 latter, a switch for the filament circuit, and a lug on the wheel adapted to disconnect the switch upon completion of the revolution by the wheel. 15
